UNITED STATES PATENT OFFICE.

EDWIN MACNEIR, OF PHILADELPHIA, PENNSYLVANIA, ASSIGNOR TO THE EDNA BRASS
MANUFACTURING COMPANY, OF CINCINNATI, OHIO, A CORPORATION OF OHIO.

WATER-GAGE.

1,335,904.

Specification of Letters Patent.

Patented Apr. 6, 1920.

Application filed October 22, 1915. Serial No. 57,280.

To all whom it may concern:

Be it known that I, EDWIN MACNEIR, a citizen of the United States, residing at 1010 S. 48th St., Philadelphia, in the county 5 of Philadelphia and State of Penna., have invented certain new and useful Improvements in Water-Gages, of which the following is a specification.

My invention consists of a novel water 10 gage in which the glass is pressure packed by the steam pressure exerted against the sides and rear face of the glass, and in which the glass is held within the gage frame by a lateral or side pressure exerted 15 on a gasket, the glass being preferably entirely out of contact with the frame.

It further consists of a novel construction and arrangement of gage frame and wedge shaped gasket whereby when the parts are 20 assembled the gasket is moved toward the sides of the glass to lock the glass in position.

My invention comprehends other novel features of construction and advantage 25 which will be clearly set forth in the detailed description.

The drawings are illustrative of a typical embodiment of my invention, but the invention is not limited to the exact arrangement and organization of the instrumentalities employed as herein shown.

Figure 1 is a front elevation of a gage 30 glass, typical of my invention. Fig. 2 is a transverse section on line X—X of Fig. 1. Fig. 3 is a sectional elevation taken on line X'—X' of Fig. 1.

Similar numerals indicate corresponding parts.

Referring to the drawings:—

40 1 designates the casing of the gage frame which has the upper nipple 2 and the lower nipple 3 in threaded engagement therewith. The nipples are extended a desired distance from the frame and are adapted to be received in the usual fittings. The nipples 2 and 3 communicate with the chamber 4 of the casing. The chamber 4 has a rear wall 5, forming a back ground for the reflex glass 6, and the end walls of the chamber 4 45 are preferably curved as seen at 7 and merge into the vertical wall 8, which merges into the wall 9 at substantially right angles to it. 10 designates the front wall of the casing, which is inclined so as to form with 50 55 the inner wall 11 of the sight member 12,

inwardly diverging walls, between which the packing or gasket 14 is located. This packing is preferably formed of a plurality of separate layers. The sight member 12 has a sight opening 15 and the converging front wall 16. The rear face of the sight member has the angular shaped recess 17, one wall of which may be, if desired, in alignment with the wall 9 of the casing. 18 is a gasket which may be dispensed with if desired, but I preferably employ a gasket of asbestos or other suitable heat resisting material, and which is interposed between the front face of the glass and the adjacent face of the sight 60 member. In the broad scope of my invention the parts may be held in assembled position in any desired manner, and in order to show one manner of accomplishing this result, I have shown a plurality of yokes 65 19, the free ends of which are deflected laterally and inwardly to coöperate with the front face of the sight member. 13 designates set screws in threaded engagement with the yokes and having their forward 70 ends adapted to abut against the casing. It will be seen that the rear wall and a portion of the lateral walls of the glass are surrounded by the steam and water pressure, so that the glass is steam packed, thereby reducing the liability of the particles of 75 80 85 the glass to fly outward in case the glass should become broken.

When the set screws 13 are tightened the wedge shaped gasket 14 is moved into firm 90 contact with the lateral faces of the glass, owing to the inclined walls 10 and 11, so that the glass is locked in position by the movement of the gasket 14 toward its side walls, which is preferably a sliding movement.

In so far as I am aware, I am the first in the art to secure the glass in position by exerting a pressure on a gasket to cause it to slide inwardly against the lateral sides 100 of the glass and to have the rear face and a portion of the lateral faces of the glass steam packed, and I wish my claims to such features to be construed with corresponding scope.

As above stated, the gasket 18 may be dispensed with as the glass is retained in position only by the pressure of the packing or gaskets 14 which are pressed laterally against the lateral walls or sides of the glass. Since 110

the pressure of the steam is exerted against the rear wall of the glass and also against a portion of the side or lateral wall, an equal pressure is imparted against the glass 5 at such points which causes it to be what I term "steam packed" or "pressure packed." The only purpose of the gasket 18 is to keep the glass out of contact with the metal of which the casing of the gage frame is made. 10 The tendency of the steam against the gasket 14 is to cause the gasket to be packed tightly against the side or lateral walls of the glass.

I claim as my invention:

1. A water gage, comprising in combination, a casing, a sight member, said casing and sight member having their adjacent faces forming walls diverging inwardly, a wedge-shaped packing between said walls, a glass between said casing and sight member, and means to clamp said sight member and casing together to cause said packing to engage only the lateral walls of said glass, whereby the rear face and a portion of the lateral walls of the glass are 25 sure packed by the steam.

2. A water gage, comprising a casing having a chamber, a sight member, said casing and sight member having their adjacent faces forming walls diverging inwardly, a wedge shaped packing between said walls, a glass forming a wall of said chamber, and means to move said packing toward the lateral walls of said glass, whereby the rear face and a portion of the 35 lateral walls of said glass are surrounded by the steam within the gage to pressure pack the glass.

3. A water gage, comprising in combination, a casing, a sight member, said casing and sight member having their juxtaposed faces inclined, a packing between said inclined faces, a glass inclosed by said casing and sight member and out of contact with said casing and sight member, and clamping 40 means for said casing and said sight member to cause said packing to slide inwardly to form a fluid tight joint with the lateral walls of the glass.

4. A water gage, comprising a casing provided with means to secure it in position, a sight member for said casing, the casing and sight member having opposed walls diverging inwardly, a glass within said casing and out of contact with the walls of the 55 sight member and the casing, a wedge-shaped packing between said diverging walls of the sight member and casing and engaging only the lateral walls of the glass, and means to clamp the parts in assembled position, to cause the packing to move laterally toward the lateral walls of the glass.

5. A water gage, comprising a casing having a chamber with an opening through 60 one wall thereof, a sight member, a glass

inclosed between the diverging walls of said sight member and casing and out of contact with said casing and sight member, the casing and sight member having opposed walls diverging inwardly, a packing having 70 inclined walls at its sides located between said sight member and casing, the inner face of said packing contacting with said glass, and means to cause relative movement of said sight member and casing to cause 75 said packing to move toward the glass.

6. A water gage, comprising a casing having a chamber opening through the side thereof, a sight member for said casing, a glass inclosed between said sight member and casing and out of contact with said casing, sealing means between said sight member and casing adapted to engage only the lateral walls of the glass, the entire rear wall and a portion of the lateral walls of said glass being at all times exposed to the water, and means to effect relative movement of said sight member and casing to cause the sealing means to engage the glass and effect a seal between the sight 90 member and the casing.

7. A water gage, comprising a casing having a chamber therein and having means to secure the gage in position, a sight member for said casing, a glass between said sight member and casing and inclosed thereby and out of contact therewith, a packing between said sight member and glass, the entire rear wall of said glass and a portion of the lateral walls of said glass being at 100 all times exposed to the water, a packing between said sight member and casing and positioned to engage the lateral walls of the glass, and means to cause the second named packing to move toward the glass and to 105 secure the sight member and casing in assembled position.

8. A water gage, comprising a casing, a sight member, said casing and sight member having inclined faces, a packing between the inclined faces of the sight member and the casing, a glass having its rear face and a portion of its lateral faces exposed to the fluid being registered, and means to secure the sight member and casing together to 110 cause the sight member to move toward the casing to cause the packing to move inwardly toward the glass between the said inclined faces to engage the lateral walls thereof and serve as the dominant factor in 115 securing the glass in position.

9. A water gage, comprising a casing, a sight member, said casing and sight member having juxtaposed inclined faces, sealing means between the inclined faces of the 125 sight member and the casing, a glass within the casing having its rear face and a portion of its lateral faces at all times exposed to the fluid being registered, and means to clamp the sight member and casing together 130

to cause the sealing means to move inwardly between the said inclined faces and engage the sides of the glass and serve as the dominant factor in securing the glass in a sealed position.

10. A water gage comprising a casing, a sight member, a glass contained within the sight member and out of contact with both the sight member and the casing, a laterally movable packing positioned between the casing and the sight member and engaging the lateral walls of the glass and exposed on one side to the pressure of the steam within the casing, the steam also surround-

ing a portion of the lateral walls of the 15 glass and its rear face to place an equal pressure on such parts, and means to move said sight member toward said casing to cause a lateral movement of the packing so as to hold the glass out of contact with 20 both the casing and the sight member.

In testimony whereof I affix my signature in the presence of two witnesses.

EDWIN MACNEIR.
